[57] CLAIM

The ornamental design for combined LCD monitor screen, industrial camera, and odor sensor for analyzing and displaying heat and odor readings for use with a computer, as shown and described.

DESCRIPTION

FIG. 1 is a front, top and right side perspective view of combined LCD monitor screen, industrial camera, and odor sensor for analyzing and displaying heat and odor readings for use with a computer, showing our new design; FIG. 2 is a rear, top and right side perspective view thereof; FIG. 3 is a front elevational view thereof; FIG. 4 is a right side elevational view thereof; FIG. 5 is a top plan view thereof; FIG. 6 is a bottom plan view thereof; FIG. 7 is a rear elevational view thereof; FIG. 8 is a left side elevational view thereof; FIG. 9 is a left side elevational view thereof with a handle in a storage position; FIG. 10 is a front elevational view thereof with a handle in a storage position; and, FIG. 11 is a bottom plan view thereof with a handle in a storage position.
